John Petheram, of New York, N.Y.

Letters Patent No. 22910 - Dated Oct. 31-1865.

Design for a Fork or Spoon handle.

The schedule referred to in these Letters Patent and making part of the same
shall also be with it may concern.

Be it known that I, John Petheram, of
the City and State of New York, have invented or produced a
new design for the handle of a spoon or fork, &c., and I do hereby de-
clare the following to be a full, clear and exact description thereof,
referring back to the annexed drawing, making part
of this specification, wherein I have represented the said
design as applied to the handle of a spoon.

The edges of the handle are ornamented with double
heads, as at 1, and the inner head passes as a scroll at 2
over the outer head and becomes itself the outer head around
the spread upper end 3 of the handle.

At the end of the scroll the heads are wider
apart and hollowed between them, terminating as a scroll
and flattened point at 4.

The heads extend to the junction of the handle
with the fork or spoon and terminate with a curved end and
scroll centre at 5.

The heads and scroll ornament on the back of the
spoon or fork handle extend along further than on the upper
side.

What I claim and desire to secure by Letters Patent is
the design for a spoon or fork handle as shown and described.

In witness whereof I have hereunto set my signature
this twenty eighth day of September 1865.

Witnesses:

Samuel W. Gorrell {
Caleb H. Smith. }

John Petheram.
